UNITED STATES PATENT OFFICE.

JOSEPH B. NEWMAN, OF RAVENNA, KENTUCKY.

TRUMPET.

Application filed June 10, 1927. Serial No. 197,885.

The present invention has reference to an improved musical instrument, and has more particular reference to a novel slide valve actuator for use upon such instruments as 5 trumpets, cornets, altos, and analogous instruments of the wind family.

For the sake of illustration, the invention is embodied in a trumpet, it being understood that it may well be incorporated in 10 similar wind instruments with equal advantage and success.

Many trumpets now marketed are equipped with finger rings built rigidly on the valve slide. Some instruments have them on the 15 first valve slide only, others on the third valve slide, and still others have them on both the first and third slides.

The purpose of the ring in either instance is to permit manipulation and adjustment 20 of the slide with a view toward permitting the sound wave passage to be shortened or lengthened, at the will of the performer in order to play in tune.

With the present style of valve slide actuating means, it is necessary to push the 25 valve slide back with the hand that holds the instrument. This is a very awkward move, cramps the player's hand, and makes it very difficult to keep the instrument in 30 correct playing position.

Usually, the means can only be used in very slow passages of music and many players will not attempt to use this feature at 35 all. Instead, they will try to make up the difference in tone by "forcing" the tone with their lips. This is not only tiresome, but produces a bad quality of tone.

Continually playing in this manner results in disability to produce round and 40 pleasant tones in proper pitch. Finally, it breaks down the performer's embouchure and reduces endurance.

My principal aim, therefore, is to substitute for the ring slide valve control, an improved manually manipulated mechanism, which is practical and efficient and capable 45 of use in exceptionally rapid passages in music.

I do not aim to create a new instrument, 50 but to merely supplement the ordinary instrument with a means that is capable of being built in, attached to the slide valve in

a manner not to interfere with the existing details.

Broadly, the invention has reference to a 55 finger control means for gradually and positively opening the slide valve, and automatic means for returning or closing the slide valve. The control means being located in a convenient place for easy actuation by one of the fingers of the hand which holds the instrument in playing position.

The particular details of the improved mechanism as well as their association and 60 arrangement of parts will become more readily apparent from the following description and drawings.

In the drawings:—

Figure 1 is a side elevation of a trumpet 70 embodying slide valve actuators on the first and third slides.

Fig. 2 is an enlarged side elevational view showing the mechanism more in detail, indicating in dotted lines, the manner in which 75 it is manipulated.

Fig. 3 is a view similar to Fig. 2, showing the finger controlled lever removed and the spring return means exposed.

Fig. 4 is a longitudinal section taken approximately upon the plane of the line 4—4 of Fig. 3, looking in the direction of the arrow.

Fig. 5 is a vertical cross section taken on the line 5—5 of Fig. 2.

Referring now to the drawings by reference characters, it will be seen that the reference character 6 designates generally the customary tubing forming a passage for the sound waves, this terminating at one end 90 in a shank for reception of the ordinary mouth piece 7, and terminating at the opposite end in the conventional bell 8. Embodied in the tubing, we find the usual piston valves 9, 10 and 11 respectively.

The reference characters 12 and 13 represent generally the first and third valve slides respectively, these being in communication with the first and third piston valves. Here, I might state that in accordance with 100 my idea, the improved slide valve actuators may be built on both the first and third valves, 12 and 13. However, a description of one will suffice for both.

To this end, it will be seen that the reference characters 14, designate the rigid tube section, upon which the U-shaped slide 15 is slidably mounted. As before stated under ordinary circumstances, this slide is provided with a rigid finger ring for pushing it in or out to vary the effective length of the sound wave passage.

In accordance with the present invention however, the ring is eliminated and the improved mechanism shown is substituted.

Specifically, the mechanism embodies a finger controlled lever, generally designated by the reference character 16. The lever is pivotally mounted as at 17 on a lug 18 formed on the tubing 6. The lever is arranged above the pivot and on one side it is formed with a finger hook 19 and formed below the pivot with a wing-like portion 20, provided with teeth providing a pinion sector.

This pinion sector is located for reception in an elongated box-like part 21 formed integral with one branch of the slide 15. Located in this box is a rack 22, the same being constructed for cooperation with the pinion teeth. Obviously, as shown in Fig. 2, by grasping the finger hook 19 and moving the lever in a direction from right to left, to the dotted line position for instance, the pinion sector and rack serve to provide and move the slide out or to open position.

It is of course necessary in order to render the device efficient, to provide means for automatically resisting this opening movement and returning the slide to closed position, the means for accomplishing this end being represented in Fig. 3. It will be noticed here that a cross piece 23 is formed integral with and bridges the tube section 14. Fastened by a tube 24 to this cross piece is a small spring anchoring arm 25 to which one end of a coiled contraction spring 26 is connected, the opposite end of the spring being connected with a toothed bar 27 extending through an opening formed in the complementary cross piece 28. Incidentally, this cross piece is formed with a single tooth 29 forming a keeper with which the teeth on the bar 27 may be selectively engaged.

Moreover the outer end of this bar 28 curves slightly and is formed with a finger-grip 30. It will be noticed that this finger grip is located so that it will not easily be engaged by obstructions accidentally releasing the bar. Also, it is so located as to facilitate grasping and manipulation.

It is evident that with this arrangement, the tension of the spring 26 can be regulated to render the action of the device more or less sensitive as desired. Fastened in any suitable manner by screws or the like to the sections 14, are small cover plates 31, which cover plates are arranged in spaced parallelism and form a housing which conceals

and encloses the spring and its regulating means.

It follows that the spring means is hardly noticeable in the actual construction of the invention. Hence, the appearance of the instrument is not detracted from by the presence of this invention.

From the foregoing description it is obvious that by placing the finger in the hook 19, the lever 16 can be rocked about the pivot 17 to bring the pinion sector and rack into play. Thus the slide 15 can be projected to the desired degree while playing.

The action of the lever is resisted by the tension of the spring, thus making the operation of the device very positive. Moreover, by proper manipulation of the lever, the slide can be allowed to return gradually or rapidly to its normal position, as desired. This result may be accomplished without cramping the hand or making it necessary to hold the instrument in an awkward position.

The advantages of a device of this class will be quite clear to persons familiar with instruments of this class. For this reason, a more lengthy description is thought unnecessary.

Minor changes in shape, size, and rearrangement of parts may be resorted to within the scope of the adjoined claims.

Having thus described my invention, what I claim as new is:—

1. In a musical instrument of the class described, a trumpet embodying customary piston valves, each including a cylinder, a piston reciprocable in said cylinder, a slide valve for at least one of said piston valves, said slide valve including spaced parallel rigid branches, and a U-shaped slide mounted thereon, a finger actuated lever pivotally mounted on a part of the trumpet adjacent said slide, a rack carried by said slide, and a pinion carried by said lever and engageable with said rack.

2. In a musical instrument of the class described, a trumpet embodying customary piston valves, each including a cylinder, a piston reciprocable in said cylinder, a slide valve for at least one of said piston valves, said slide valve including spaced parallel rigid branches, and a U-shaped slide mounted thereon, a finger actuated lever pivotally mounted on a part of the trumpet adjacent said slide, a rack carried by said slide, and a pinion carried by said lever and engageable with said rack, together with adjustable spring means for resisting the actuation of said lever and for returning said slide to normal closed position.

3. In a structure of the class described, a trumpet embodying a slide valve including spaced parallel rigid branches and a slidably mounted U-shaped slide, spring means located between said branches and having adjustable connection with said slide,

a rack carried by one arm of said slide, a pivotally mounted lever having finger operating means and a toothed sector, the teeth of which are in mesh with the teeth of said rack.

4. In a structure of the class described, a trumpet embodying a slide valve including spaced parallel rigid branches and a slidably mounted U-shaped slide, spring means located between said branches and having ad-

justable connection with said slide, a rack carried by one arm of said slide, a pivotally mounted lever having finger operating means and a toothed sector, the teeth of which are in mesh with the teeth of said rack, and removable cover plates for housing and concealing said springs. 15

In testimony whereof I affix my signature.

JOSEPH B. NEWMAN.
